UNITED STATES PATENT OFFICE.

HOWARD L. DAVIS, OF PLUMSTEAD TOWNSHIP, OCEAN COUNTY, NEW JERSEY,
ASSIGNOR TO HAROLD L. WATSON, OF LANCASTER, PENNSYLVANIA.

INCUBATOR.

1,283,402.

Specification of Letters Patent.

Patented Oct. 29, 1918.

Application filed August 30, 1913. Serial No. 787,422.

To all whom it may concern:

Be it known that I, HOWARD L. DAVIS, of Plumstead township, in the county of Ocean and State of New Jersey, have invented certain new and useful Improvements in Incubators, whereof the following is a specification, reference being had to the accompanying drawings.

The invention relates more particularly to incubators wherein there are a plurality of compartments so that the capacity of the incubator may be very great.

An object of the invention is to provide an incubator having a compartment provided with means for regulating and proportioning the heat, air and moisture supplied to the compartment.

A further object of the invention is to provide an incubator of the above character with a hot water heating system which includes means for maintaining the water passing through the system at a predetermined temperature.

These and other objects will in part be obvious and will in part be hereinafter more disclosed.

In the drawings, which show by way of illustration one embodiment of the invention, Figure 1, is a front elevation of an incubator embodying the improvements.

Fig. II, is a partial plan view of the same.

Fig. III, is an end view showing the heating plant in side elevation.

Fig. IV, is a transverse sectional view through the incubator.

Fig. V, is a longitudinal sectional view through a portion of the incubator showing the parts on an enlarged scale.

Fig. VI, is a top plan view of one of the trays showing the manner of supporting the same.

Fig. VII, is a transverse sectional view through the tray.

Fig. VIII, is a longitudinal sectional view through one of the trays showing the adjustable partition.

The invention consists, broadly, in providing an incubator which comprises a plurality of compartments arranged end to end and side to side, and also above each other. The compartments forming the upper tiers are spaced from the lower compartments and are in no way connected therewith. In other words, except for the manner of heating the compartments, each compartment is venti-

lated and the moisture supplied thereto separately and independently controlled from the others. Each compartment is provided with an ingress opening through which fresh air is admitted to the compartment. The fresh air passing to the compartment is led over a tray of water which is preferably heated to a predetermined temperature and moisture is thereby conveyed by the air into the compartment. The temperature of the compartment is regulated by a thermostat which is connected to a damper. The opening of the damper to a greater extent allows the heated air to escape and more fresh air to pass into the compartment.

In each compartment there are pivoted trays which support the eggs and these trays may be readily turned by mechanism extending outside of the compartment. This mechanism, which may be of any desired character, is so constructed that all of the trays in each compartment may be simultaneously turned and said mechanism also includes devices whereby one or more of these trays may be disconnected from its turning mechanism and locked in fixed position.

Referring more in detail to the drawings, the improved incubator consists of a casing 1, which is mounted on suitable supporting legs 2, and is divided into compartments. The incubator, also, as herein shown, includes a second casing 3, which is mounted on supporting legs 4, which are in turn mounted on the top of the lower casing, thus forming a double deck incubator. Each casing is divided by longitudinal partitions 5 and 6, see Fig. IV, and also by transverse partitions 7. This forms compartments 8, located side by side and end to end. The partitions 5 and 6 are separated so as to form a space 9, which is closed at the top by the upper wall of the casing. This space is open at the bottom, as at 10. The partition 5 is provided with a series of apertures 11, which allow fresh air to pass through the space 9 and through the apertures 11 into the compartments 8, with which said apertures are connected. The partition 6 is provided with a series of apertures 12 for a similar purpose. A distributing or baffle plate 13 is located between the partitions and extends to a point slightly below the openings 11 and 12, and this divides and equally supplies and distributes the air to the compartments, and prevents short cir.

cuiting between any two adjacent compartments.

Each of the compartments is also provided with an egress opening 14, through which the air in the compartment is allowed to escape. This opening is controlled by a damper 15. The damper 15 is supported by an arm 16, which is in turn connected to a thermostat 17, preferably of the diaphragm type, located in the compartment. This thermostat is so proportioned and connected to the damper that when the temperature in the compartment increases the damper will be raised to allow the heated air to escape. 10 This causes fresh air to enter the compartments through the ingress openings and thus bring the temperature of the compartments back to the desired predetermined point. I have shown the opening 14 as disposed at the 20 opposite side of the compartment from the apertures through which the air enters the same. It will be obvious, however, that this opening 14 may be otherwise located, the essential feature being an opening through 25 which the air may readily pass, which opening is controlled by a damper automatically positioned by the temperature in the compartment.

The moisture supplied to the compartments is also automatically controlled. Extending beneath the casing 1 is a trough 19, which is adapted to contain water, as indicated in Fig. IV. This trough is disposed directly beneath the opening 10 leading into 30 the passage 9, through which air enters the compartments. It is slightly spaced from the lower wall of the casing so as to permit the air passing to the compartments to pass over the surface of the water in the trough 35 and thus become more or less saturated with moisture depending upon the temperature of the water and the rapidity with which the air passes into the compartments. It is well known that slow steady current of air over 40 a body of water, because of its sluggish circulation, carries with it much more moisture than where the air passes rapidly over the surface of the water. Therefore, the rapidity with which the air is changed in the compartments will vary inversely the amount of 45 moisture carried into the compartments by the inrushing air for a given volume of air. In other words, when the temperature is relatively low, in the compartment, the amount of moisture or humidity of the air is greater and on the other hand, when the temperature of the air is relatively high, the amount of moisture in the air or humidity 50 will be relatively low.

60 I have provided a heating system for each compartment which is so regulated that the heat supplied said compartments from said system is substantially uniform. At the beginning of the hatch, there is little heat 65 from the eggs and very little expansion of

the thermostat, and the damper opens very little beyond its normal set position. This causes a slow steady circulation of air over the moisture trough into the compartment. This steady slow current of air carries with it much moisture into the compartment and to the eggs, which is the desired condition at this time of the hatch. As the hatch progresses a greater amount of heat is developed in the eggs, which causes an expansion of the thermostat and enlarges the opening controlled by the damper, which causes a faster circulation of air through the compartment and over the moisture trough. This supply of fresh air increases the air 80 cells in the eggs and provides more room and more air to strengthen the chicks, and also decreases the moisture in the air. In other words, by the devices above described I am able to automatically increase the ventilation and decrease the moisture in the air as the hatch progresses.

The heating system, as shown in the drawings, consists of a heater 20, which maintains substantially a uniform degree of heat. 90 This heater is provided with a water circulating system which is connected by pipes 21 to pipes 22 leading in and about the top of each compartment in the lower casing. Pipes 23 are connected with pipes 24, which 95 lead in and about each compartment in the upper casing. The hot water system is also provided with an expansion chamber 25, having a float which is connected with a lever 26, which is moved to control certain 100 connections 27 and 28 to the dampers for the heater which automatically maintains the water in the system at a predetermined temperature. The water in the troughs 19 is heated by a pipe 29, and this pipe is also 105 connected to a separate water system in the heater 20. The temperature of the water in the pipe 29 may be determined by a thermometer 30. I have shown in each of the upper compartments a radiating plate 31, 110 which is located beneath the heating pipes and causes an even distribution of heat through the compartments before leaving the same. In order to control the flow of water and hence the temperature in the upper incubator section, I have provided the inlet and outlet pipes 28 with the valve 32. By this means, the flow of water in the upper section can be independently controlled and the temperature in the said upper section is maintained uniform with that of the lower section. If it were not for this method of control, the temperature of the upper section would always be higher than that of the lower section, owing to the tendency of the heated water to rise to the highest point. 120

125 From the above it will be obvious that the circulation of water in the upper section will be greater than that of the lower section. 130

hence the necessity of the valve control to regulate the temperature of this upper section to correspond with that of the lower section.

- 5 From the above description, it will be apparent that I have provided an incubator with a heating system wherein the amount of heat supplied to each compartment may be kept uniform or changed as desired, to 10 meet the different conditions through the entire period of incubation. I have also provided means whereby the temperature in the compartment may be automatically regulated, and this automatic regulation of the 15 temperature also controls the amount of fresh air and the amount of moisture supplied to the compartment. This automatic control of the heating element, also of the temperature of the compartment, and also 20 the automatic control of the fresh air and the moisture supplied, contribute jointly if they are properly proportioned to a greater efficiency in the hatch.

The eggs are supported in the compartments by trays 33. These trays 33 may be of any desired construction so as to permit free access of air to the eggs therein, and so that the trays may be turned either side up and still maintain and properly support the 30 eggs. As herein shown, each tray consists of a frame which is formed in two sections 34 and 35. Each section is provided with a wire netting 36, on one of which the eggs rest and the other holds the eggs in place 35 thereon. The eggs are placed in one section of the tray and then the other section is placed on the first section and this, as above noted, holds the eggs.

These trays are adapted to be received by 40 supports each of which comprises end members 37 and 38, joined by suitable spacing bars 39. The end members 37 and 38, are provided with trunnions 40, whereby the supports are pivotally secured to the lateral 45 dividing partition. The trays are received between paired projections or ledges 41 and 42, formed integrally with the end members 37 and 38. The ledges 41 are provided with springs 43, which engage the trays and hold 50 them firmly in position in the supports. The extent to which the trays may be slid into the supports is determined by lugs or stops 45, which are secured to the upper and lower members of the tray and engage with ends 55 of the ledges 41 and 42, on the members 37 and 38, as best shown in Fig. VII. These stops also prevent sidewise shifting of the trays during turning.

The member 38, at one end of the tray 60 support, is in the form of a gear 47. In each compartment, as herein shown, there are two trays and these trays are of such size and so disposed in the compartments that they may be rotated or turned upside 65 down or at any angle desired. The gears 47

mesh with an operating gear 50, which is connected to a shaft 51, extending from end to end of the casing. This shaft 51 is connected to the gears 50 in each casing, so that all of the gears 50 may be simultaneously 70 rotated and thereby all of the trays simultaneously turned. The gear 50 is secured to the shaft 51 by means of a set screw 52, so that the said gear may be disconnected from the shaft 51 by loosening the set screw, so 75 that the trays in any one or more compartments may be disconnected from the shaft 51 and therefore remain in fixed position.

The trays are provided with adjustable partitions 55, so that the eggs are held in 80 fixed position and are thereby prevented from shifting during the turning process. The adjustability of these partitions will also permit of the partial filling of the trays. After adjusting, these partitions are 85 held in fixed positions by pins 56, which engage in the meshes of the wire nettings 36 as shown in Fig. VIII.

From the above, it will be understood that the trays are so constructed that they are 90 held in fixed position in their supports. These trays may be readily turned so as to be placed at any desired angle or turned entirely over and by this adjustment of the tray the eggs may be properly positioned 95 and turned as is necessary during the period of incubation.

In the present instance, the trays are moved through an angle of 180 degrees and back again, and the stops 45 are thereby effective in preventing the trays from sliding 100 from their supports during the turning operation.

Each compartment is provided with a door, indicated at 60, whereby access may be 105 had to the trays. It will be understood that the upper tier of compartments is entirely independent of the lower tier of compartments, and is merely supported on the lower casing as a matter of convenience and to 110 economize space.

The operation of my device is thought to be clear from the above detailed description of the construction and also from the description of the manner of operation of the 115 different devices which contribute to making up the assembled construction. Through the coöperation of the various features described in detail, I have provided an incubator in which the capacity is very great 120 and in which the efficiency of the hatch is a maximum. It will be obvious that minor changes in the details of construction and the arrangement of the parts may be made without departing from the spirit of the invention as set forth in the appended claims.

Having thus described my invention, I claim:

1. An incubator apparatus comprising a 130 casing having partitions therein forming

- 4 compartments arranged end to end and side to side, a heating system for said incubator automatically controlled at a uniform temperature, including heating pipes located in the upper portion of said compartments, egg supporting means located in said compartment beneath said heating pipes, said casing having means located below said pipes for admitting fresh air to the compartment and an opening to permit air to escape therefrom, a damper for controlling said last-mentioned opening and a thermostat for each compartment located wholly within each compartment and connected by a suitable mechanism to said damper for simultaneously controlling the temperature of the compartment and the amount of fresh air supplied thereto independently of said automatically controlled heating system, said damper being capable of substantially entirely shutting off the supply of fresh air to the compartment.
2. A mammoth incubator comprising in combination, a plurality of compartments, a heating system common to each of said compartments, automatically controlled at a uniform temperature, egg-supporting means located in each of said compartments, means for admitting fresh air to each compartment, each of said compartments being provided with an opening to permit air to escape therefrom, a damper for controlling said last-mentioned opening, thermostatically operated means for each compartment connected by suitable mechanism to said damper for regulating both the temperature in a compartment and the amount of fresh air supplied thereto independently of said automatically controlled heating system and means for moistening the air as it is supplied to a compartment, said thermostatically operated means in each compartment being wholly independent of every other compartment, said mechanism arranged so as to be capable of shutting off the entire fresh air supplied to the compartments.
3. A mammoth incubator comprising in combination, a plurality of compartments, a heating system common to each of said compartments automatically controlled at a uniform temperature, egg-supporting means located in each of said compartments, means for admitting fresh air to each compartment, each of said compartments being pro-

vided with an opening to permit air to escape therefrom, and thermostatically operated means for each compartment for regulating both the temperature in a compartment and the amount of fresh air supplied thereto independently of said automatically controlled heating system and independently of every other compartment including means capable of substantially entirely shutting off the supply of fresh air to the compartment.

4. An incubator apparatus comprising a casing having partitions therein forming compartments arranged end to end and side by side, said compartments arranged side by side being spaced to permit the passage of air therebetween to an aperture in the side walls through which the air passes into the compartment, means between said walls separating said apertures, said casing having openings through which the air may escape from said compartments, a damper for controlling each of said openings, a thermostat in each compartment for positioning said damper, trays in each compartment, a trough adapted to contain water, and means for supporting said trough whereby the air passing to the compartments is led over the surface of said water.

5. In an incubator apparatus, a casing having partitions therein forming compartments arranged side by side and end to end, said compartments arranged side by side being spaced to form an air chamber, and each wall of said compartments adjacent said chamber being provided with an aperture communicating with the interior of said compartment and with said chamber, a deflector in said chamber separating said apertures, the device being so arranged as to permit the passage of air from the upper part of the interior of said compartment, means operative to control said passage of air, and a thermostat in said compartment for automatically controlling said controlling means in conformity with the temperature of the compartment.

In testimony whereof, I have hereunto signed my name at Philadelphia, Pennsylvania, this 27th day of August 1913.

HOWARD L. DAVIS.
